CLAIM

The ornamental design for a knee joint for prostheses, as shown and described.

DESCRIPTION

FIG. 1 is a first perspective view of a knee joint for prostheses in accordance with aspects of the present disclosure.

FIG. 2 is a first side view of the knee joint for prostheses in accordance with aspects of the present disclosure.

FIG. 3 is a rear side view of the knee joint for prostheses in accordance with aspects of the present disclosure.

FIG. 4 is a second side view of the knee joint for prostheses in accordance with aspects of the present disclosure.

FIG. 5 is a bottom view of the knee joint for prostheses in accordance with aspects of the present disclosure.

FIG. 6 is a front view of the knee joint for prostheses in accordance with aspects of the present disclosure.

FIG. 7 is a top view of the knee joint for prostheses in accordance with aspects of the present disclosure; and,

FIG. 8 is a second perspective view of the knee joint for prostheses in accordance with aspects of the present disclosure.

Any subject matter shown in dashed lines, and any surfaces of the design not shown, including interior surfaces, form no part of the claimed invention.
